Sales Company, Salt Lake City, Utah, a corpo-
ration of Utah

Application July 7, 1938, Serial No. 78,323

Term of patent 14 years

To all whom it may concern:

Be it known that I, Frank G. Steiner, a citizen
of the United States, residing at Chicago, in the
county of Cook and State of Illinois, have in-
vented a new, original, and ornamental Design
for a Mount Plate for Supply Rolls, of which the
following is a specification, reference being had
to the accompanying drawing, forming part
thereof, and in which

Figure 1 is a front elevational view of the
article, showing my design;

Figure 2 is a side elevational view;

Figure 3 is a rear elevational view; and

Figure 4 is a top plan view thereof.

I claim:

The ornamental design for a mount plate for
supply rolls, substantially as shown.

F. G. STEINER.
